ABSTRACT OF THE DISCLOSURE

A new detergent composition comprising, in combination, a water-insoluble metal salt of amphoteric surface active agent and a substance capable of dispersing and solubilizing this metal salt in water. This composition may be used either independently or by being included in any known detergent. In this latter instance, the detergency, bubble-forming ability and duration of bubbles of the base detergent are greatly improved. In particular, laundry which is cleansed with this composition either directly or jointly with a known detergent is invariably bestowed with an antistatic property, a resistivity to re-soiling and a soil-releasability.

BACKGROUND OF THE INVENTION

(a) Field of the invention

The present invention is concerned with a detergent, and more particularly, it relates to a new detergent composition having an improved amphoteric surface active agent as its active component.

(b) Description of the prior art

In general, it has been the practice to wash natural fibers and man-made fibers with either an anionic surface active agent such as a sodium salt of alkylbenzene sulfonate or a non-ionic surface active agent such as nonyl phenol ethylene oxide adduct. However, in case these known detergents were used, the fibers cleansed with such a detergent invariably presented a deteriorated hand feel and/or a loss of antistatic property. Therefore, it has been the usual practice to give the washed fibers an additional treatment with a soft-finishing agent and/or an antistatic agent. However, these properties which were thus added to the fibers disappeared when the fibers were washed again. On the other hand, in case the fibers were washed with known detergent mixed with a soft-finishing agent and an antistatic agent, the individual effects of these mixed detergents were not exhibited clearly but rather they served, in many cases, only to lowering of the activity of the detergent per se. Therefore, in case it was intended to use a soft-finishing agent and/or an antistatic agent, it was necessary to add these agents in a rinsing solution after cleansing or to subject the washed fibers to a separate treatment with these agents, and thus a great inconvenience was experienced.

The inventor had already accomplished a method of imparting an antistatic property to plastics by the inclusion—in a plastic by kneading—of a substance having the general formula:

wherein:

2

R represents a hydrocarbon group having 6-22 carbon atoms,

M represents a metal,

l represents an integer, and

5 x, y each represents an integer determined by the valency of the said metal.

This prior invention of the author was published under Japanese patent publication No. 10,327/1963.

However, the substance having the aforesaid chemical 10 Formula I or its compounds are of a high melting point and are water-insoluble. Thus, it was impossible to impart an antistatic or other useful properties to high polymers externally thereof in an aqueous solution by the use of the said substance or its compounds.

SUMMARY OF THE INVENTION

The author made an extensive research in order to find means of effecting the deposition or the adsorption of the 20 said substance having the chemical Formula I onto the surface of a polymer—which is intended to be given an antistatic property—externally of the surface of the polymer in an aqueous solution without kneading this substance into the polymer. By the use of an effective dispersing agent, the author solubilized and partially dispersed a water-insoluble substance in an aqueous solution to prepare a transparent aqueous solution containing this substance in the state of being dispersed and solubilized therein. By destroying the resulting emulsion and then 30 bonding the particles of this substance in this aqueous solution onto the surface of a polymer, the substance was deposited in an adsorbed state on the surface of the polymer externally. As a result, the author succeeded in forming a water-insoluble molecular surface layer of the said substance on the surface of the polymer.

35 According to the author's research—which was reported in Kogyo Kagaku Zasshi, vol. 68, p. 2186, (1965), it was found that the substance having the chemical structure (I) could be modified—in case the substance was an alkali earth metal salt such as a salt of calcium or barium—into a quite stable substance having the following chemical formula which was an acid salt of a metal salt of amphoteric surface active agent:

55 It is, therefore, a primary object of the present invention to provide a new detergent composition not only having satisfactory detergency, bubble formability and bubble durability which are essential requirements of a detergent, but also having the capability of imparting to laundry which is cleansed with it an antistatic property, resistivity to re-soiling and soil releasability.

Another object of the present invention is to provide 60 a new detergent composition of the type described, which not only can be used independently as a detergent, but also which, when included in a small amount in any known detergent, fully exhibits the aforesaid desirable effects.

65 Still another object of the present invention is to provide a new detergent composition of the type described, which gives laundry which is cleansed with it a long-staying antistatic property, resistivity to re-soiling and soil releasability and which, thus can display the same useful 70 effects for practical purposes as those exhibited by laundry which is given an additional antistatic and other treatments after being washed.

3

These as well as other objects, advantages and features of the present invention will become apparent by reading the following detailed description of the preferred embodiments.

DETAILED DESCRIPTION OF THE PREFERRED EMBODIMENTS

The present invention contemplates the provision of a new detergent composition which is prepared by the use of at least one of those water-insoluble metal salts of amphoteric surface active agent which are expressed by the general formulas:

5 wherein:

m represents an integer 1-3;
R' represents hydrogen or CH_3 ;
X represents hydrogen or $(\text{CH}_2)_m \text{COO}$; and
p represents an integer 1 or 2

10 and blending the aforesaid water-insoluble metal salt to at least one of the substances expressed by the general formula:

15 wherein:
R represents a hydrocarbon group having 6-30 carbon atoms;
R' represents hydrogen or CH_3 ;
p, q, r each represents an integer 3-100;
b represents an integer 1 or 2;
k represents an integer 0 or 1;

and

wherein:

R represents a hydrocarbon group having 6-30 carbon atoms;
R' represents hydrogen or CH_3 ;
m represents an integer 1-3;
p represents an integer 1 or 2;
X represents hydrogen or $(\text{CH}_2)_m \text{COO}$ or $(\text{CH}_2)_m \text{COO}$

*X*₁ may be *X* or nothing; in the latter case there is present no OH group bonded to nitrogen;
b represents an integer 1 or 2;
k represents an integer 0 or 1;
q, r each represents an integer 0 or 1 or 2;
l represents an integer 0 or 1-5;
s represents an integer 1-4;
M represents an alkali earth metal;
x, y, z each represents an integer determined by the valency of the said metal; and
A represents either $-(\text{CHR}'\text{CHR}'\text{O})_p \text{X}$ or

and blending the aforesaid water-insoluble metal salt to amphoteric surface active agent having, in the molecules thereof, the following common group:

4

5 wherein:
m represents an integer 1-3;
R' represents hydrogen or CH_3 ;
X represents hydrogen or $(\text{CH}_2)_m \text{COO}$; and
p represents an integer 1 or 2

10 and blending the aforesaid water-insoluble metal salt to at least one of the substances expressed by the general formula:

15

$$\begin{array}{c}
 \left[\begin{array}{c} \text{R}-\text{C} \quad \text{N}-\text{CH}_2 \\ \diagup \quad \diagdown \\ \text{HO} \quad \text{N}-\text{CH}_2 \\ \diagdown \quad \diagup \\ (\text{CH}_2)_m \text{COO} \quad (\text{CHR}'\text{CHR}'\text{O})_p \text{X}_3 \end{array} \right]_k \left[\begin{array}{c} \text{X}_1 \quad \text{OH} \\ \diagup \quad \diagdown \\ \text{N}-\text{CH}_2 \\ \diagdown \quad \diagup \\ (\text{CH}_2)_m \text{COO} \quad (\text{CHR}'\text{CHR}'\text{O})_q \text{X}_4 \end{array} \right]_b \left[\begin{array}{c} \text{X}_2 \quad \text{OH} \\ \diagup \quad \diagdown \\ \text{N}-\text{CH}_2 \\ \diagdown \quad \diagup \\ \text{A} \end{array} \right]_r \text{My} \\
 \text{[(VII) }
 \end{array}$$

20 wherein:
R represents a hydrocarbon group having 6-30 carbon atoms;
R' represents hydrogen or CH_3 ;
p, q, r each represents an integer 3-100;
b represents an integer 1 or 2;
k represents an integer 0 or 1;

$$\left[\begin{array}{c} \text{R}-\text{C} \quad \text{N}-\text{CH}_2 \\ \diagup \quad \diagdown \\ \text{HO} \quad \text{N}-\text{CH}_2 \\ \diagdown \quad \diagup \\ (\text{CH}_2)_m \text{COO} \quad (\text{CHR}'\text{CHR}'\text{O})_p \text{X} \end{array} \right]_k \left[\begin{array}{c} \text{O} \quad \text{X}_1 \\ \diagup \quad \diagdown \\ \text{N}-\text{CH}_2 \\ \diagdown \quad \diagup \\ (\text{CH}_2)_m \text{COO} \quad (\text{CHR}'\text{CHR}'\text{O})_q \text{X} \end{array} \right]_b \left[\begin{array}{c} \text{O} \quad \text{A} \\ \diagup \quad \diagdown \\ \text{N}-\text{CH}_2 \\ \diagdown \quad \diagup \\ (\text{CH}_2)_m \text{COO} \quad (\text{CHR}'\text{CHR}'\text{O})_r \text{X} \end{array} \right]_l \text{My} \\
 \text{[(V) }
 \end{array>$$

25 *s* represents an integer 1-4;
M represents an alkali metal or a non-alkali metal;
x, y, z each represents an integer determined by the valency of the metal;
A represents either $-(\text{CHR}'\text{CHR}'\text{O})_p \text{X}_6$ or

$$\begin{array}{c} \text{R}-\text{CH}-\text{CH}_2- \\ \diagup \quad \diagdown \\ \text{O} \quad (\text{CHR}'\text{CHR}'\text{O})_p \text{X}_7 \end{array}$$

30 *X*₁, *X*₂, *X*₃, *X*₄, *X*₅, *X*₆, *X*₇ each represents hydrogen or $(\text{CH}_2)_m \text{COO}$ (wherein: *m* represents an integer 1-3; at least one of *X*₁, *X*₂, *X*₃, *X*₄, *X*₅, *X*₆, *X*₇ is $(\text{CH}_2)_m \text{COO}$; in case *X*₁ and *X*₂ are not $(\text{CH}_2)_m \text{COO}$, nitrogen, will be tertiary nitrogen),

35 and by solubilizing and dispersing the resulting mixture in water in partially solubilized condition. This composition may be used widely as a detergent either independently or by being added in any known detergent, in each of which instances the composition will exhibit an excellent detergency, bubble formability and bubble durability for laundry which is washed with this composition, and moreover, it can give the laundry an antistatic property, a resistivity to re-soiling and a soil releasability of a prolonged duration.

40 In other words, the detergent composition of the present invention may be regarded as a sort of polymeric elec-

troyte or polymeric surface active agent, and can be considered to present a dispersion system of high molecular weight micelles, in a solution, of at least one of the aforesaid substances expressed by the general Formulas III, IV, V and VI. Accordingly, the critical micelle concentration of these substances for micelle formation is very low, which appears to be in the order of $1/100$ – $1/1000$ of the critical micelle concentration of sodium alkylbenzene sulfonate. Thus, the detergent composition of the present invention exhibits surface activity at a very low concentration thereof and displays a satisfactory detergency. Furthermore, solubilization and destruction of dispersion take place at the laundry/washing solution and air/washing solution interfaces, and as a result, a water-insoluble and firm mono-molecular layer is formed by adsorption of the said composition onto the surface of the laundry.

Accordingly, bubbles which are firm and yet durable are formed very easily. Along with this, a tough mono-molecular layer of the substance of either (III), (IV), (V) or (VI) is formed in the same way at the surface of the laundry. Thus, the laundry is imparted an antistatic property and at the same time the laundry is effectively prevented from re-deposition thereon of the soil components, especially of oily soil, having been detached previously therefrom, thus developing a high re-soiling preventability or soil releasability.

In view of the fact that this mono-molecular surface layer of the substance of (III), (IV), (V) or (VI) is insoluble in water and is firm, it is held stably at the surface of the laundry in the rinse process also. Moreover, the said layer is stably held thereat continuously after the laundry is dried. Thus, the layer of the said substance is able to impart the laundry an antistatic property as well as a soil releasability for an extended period of time. As such, the detergent composition of the present invention can be used independently as a finishing agent for the purposes of antistatic treatment, anti-resoiling treatment, soil-release treatment and/or softening treatment. Such properties of the composition of the present invention can be as equally exhibited in case it is added to known detergent compositions as is exhibited in case it is used alone. As an example of especially effective instances, this composition is added to a known carpet shampoo consisting mainly of sodium salt of alkyl sulfate. By doing so, ex-

5 tremely stable bubbles are formed, and moreover, it is possible to have the soil components adsorb or deposit onto the surfaces of the bubbles effectively, and also, after the bubbles have been removed by a vacuum suction device, the carpet surfaces will have excellent antistatic property and soil-releasability.

10 As the metal in (III)–(VI) in the present invention, metals other than alkali metals which form water-insoluble metal salts having a high melting point are selected as a principle. More desirably, the use of an alkali earth metal such as calcium and barium is suitable. By the use of an alkali earth metal, it should be understood that (III) and (V) can form acid salts in the form of (IV) and (VI), respectively.

15 Hereunder are shown typical substances in order to explain the general Formula V in further detail.

Accordingly, in order to explain the general Formula VI in further detail, its typical substances are shown as follows:

The metallic group which can be used in (VII) may 50 consist of the same metallic group as those stated above so as to correspond to those in (III), (IV), (V) and (VI), respectively. However, it is also possible to utilize those metallic groups of alkali metals and non-alkali metals of a broad range.

In order to explain the general formula of (VII), its typical substances may be enumerated as follows:

Solubilization and dispersion in water may be accomplished by first heating at least one of the substances (III) through (VI) to a temperature of 80-120° C. (in case the substance is of a high melting point, it is heated at a temperature above 120° C. but about 5° C. lower than its melting point) in either anhydrous state or hydrous state, thereafter adding thereto a substance of (VII)

heated to the same temperature while stirring the mixture thoroughly and cooling same down to 80-90° C., and adding a predetermined amount of water of the same temperature, followed by a thorough stirring and cooling the resultant mixture to room temperature. Desirably, this mixture is further passed through a colloid mill or a homogenizer in order to obtain a much better and more stable aqueous dispersibility.

An even more desirable composition of the present invention may be obtained by adding to the aforesaid composition a metal salt (such as a salt of lithium, potassium or calcium) of acylated amino acid or other surface active substances.

EXAMPLE 1

10 parts by weight of a compound having the above-mentioned structural formula were heated at 100° C. and melted. While stirring, 2.2 parts of a substance selected from those having the structural formulas (A) through (F) mentioned below and held at the same temperature were added thereto to melt the added substance uniformly. Then, 87.8 parts of boiling water which was prepared separately were added little by little while stirring to dilute the mixture. After the completion of the addition, the resulting mixture was passed once through a homogenizer and was cooled to normal temperature. As a result, a paste-like composition was obtained.

Pieces of knitted fabric made of acrylic fibers (a product of Mitsubishi Rayon Co., Ltd. of Japan, marketed under the trade name of Vonnell) were allowed to sustain deposition thereon of an oily soil consisting of liquid paraffin:soya bean oil=1:1. Thereafter, these soiled

pieces of knitted fabric were washed by an electric washing machine. The result is shown in Table 1.

EXAMPLE 10

EXAMPLE 13

wherein R represents a saturated hydrocarbon having 18-26 carbon atoms.

To 8 parts by weight of a compound having the above-mentioned structural formula was blended 1 part of a compound selected from (A) through (F) in the same manner as that in Example 1, followed by dilution with 90 parts of water, and thus the desired liquidous composition was prepared. In the same manner as that in Example 1, a washing test was conducted. The result was that superior hand feel, detergency and antistatic property same as those in Example 5 were noted.

EXAMPLE 14

wherein R represents a saturated hydrocarbon having 18-26 carbon atoms.

To 7 parts by weight of a compound having the above-mentioned structural formula were blended 3 parts of a compound selected from (A) through (F) of Example 1, followed by being diluted with 90 parts of water to prepare the desired composition. In the same manner as that in Example 1, a washing test was conducted. The result showed superior effects as in Example 6.

35

wherein R represents a saturated hydrocarbon having 14-16 carbon atoms.

30

To 9 parts by weight of a compound having the above-mentioned structural formula was added 1 part of a compound selected from (A) through (F) in the same manner as that in Example 1, followed by dilution with 90 parts of water to prepare the desired composition. A washing test was conducted by the use of this composition. The result showed as satisfactory effects as those demonstrated in Example 10.

EXAMPLE 15

To 8 parts by weight of a compound having the above-mentioned structural formula were blended 2 parts of a compound selected from (A) through (F) in the same manner as that in Example 1, followed by dilution with 90 parts of water to prepare the desired composition. A washing test was conducted with this composition. The result was that superior effects as those in Example 7 were exhibited.

EXAMPLE 16

45

Commercial detergent used in this example had the following composition: 12% of sodium salt of linear alkylbenzene sulfonate, 15% of sodium tripoly-phosphate and an amount of Glauber's salt which was increased to 63%. To a batch of this commercial detergent composition was added 10% of a composition selected from those obtained in the above-mentioned examples, i.e., the composition containing (B) and the composition containing (E) in Example 1; the composition containing (B) and the composition containing (E) in Example 2; the composition containing (B) and the composition containing (E) in Example 4; and the composition containing (B) and the composition containing (E) in Example 12. They were added, respectively, one for one batch. Thus, detergent compositions were prepared. By the use of these re-

To 9 parts by weight of a compound having the above-mentioned structural formula was added 1 part of a compound selected from (A) through (F) in the same manner as that of Example 1, followed by dilution with 90 parts of water. Thus, desired composition was prepared. This was subjected to a washing test, with the result that superior effects as those in Example 8 were noted.

55

70

75

spective detergent compositions, washing tests were conducted on pieces of soiled polyester cloth (these pieces of cloth—product of Teijin Co., Ltd. of Japan—were attached to the inner side of the collar of shirts and worn by persons consecutively for a week to become soiled) in the same manner as that described in Example 1. The result of these tests is shown in Table 11.

TABLE II

Antistatic property				
	Percent- age of soil removed	Half time of leakage (second)	Surface resistiv- ity (Ω)	Soft- ness (hand feel)
Detergent.....				
(B), Example 1.....	98	0.1	2.0×10^9	Soft.
(E), Example 1.....	98	0.2	4.5×10^9	Do.
(B), Example 2.....	97	0.2	7.3×10^9	Do.
(E), Example 2.....	96	0.3	1.0×10^{10}	Do.
(B), Example 4.....	98	0.1	8.6×10^9	Do.

EXAMPLE 20

Carpet cleaning solution having the following two types of compositions were prepared.

Detergent composition of the present invention:	Percent
Composition of the invention	0.1
Sodium salt of lauryl sulfate	0.425
Lauroyl diethanolamine	0.15
Water	Balance
Control composition:	
Sodium salt of lauryl sulfate	0.5
Lauroyl diethanolamine	0.15
Water	Balance

By the use of these two types of detergent compositions, soiled light brown carpets made of nylon fibers were washed according to ordinary carpet washing method, i.e., bubble formation-brushing-leaving them lying in bubbles-vacuum suction. The result of the washing test is as shown in Table 12.

TABLE 12

Detergent	Degree of soil removed	Moisture removability upon completion of washing	Half time of leakage (seconds)	Re-soil ¹ (days)
(B), Example 1.....	Good.....	Fresh and light; dried quickly.	1.2	67
(E), Example 1.....	do.....	do.....	1.0	55
(B), Example 2.....	do.....	do.....	0.5	70
(E), Example 2.....	do.....	do.....	0.1	65
(B), Example 4.....	do.....	do.....	0.6	55
(E), Example 4.....	do.....	do.....	1.0	60
(B), Example 12.....	do.....	do.....	1.0	65
(E), Example 12.....	do.....	do.....	0.8	70
Control.....	Still had some soil.	Very wet when touched	∞	18

¹ Carpets were laid at the entrance of a building. The number of days required for being soiled to almost the same degree as noted before being washed was calculated from an floor test. The carpets were, however, cleaned once every day by an electric cleaner.

EXAMPLE 21

Hair shampoo compositions were prepared by adding 10% of the compositions of the present invention (containing 90% of water) to batches of the following hair shampoo composition:

	Parts	70
Triethanol amine lauryl sulfate	8	
Lauroyl diethanolamine	3	
Urea	8	
Sodium salt of tri-lauryl alcohol ether surface	3	
Water	Balance	78

Hair was washed with these compositions, respectively. The result is shown in Table 13.

TABLE 13

		Static frictional coeffi- cient	Hand feel	Condi- tion of foam
5	Shampoo

EXAMPLE 22

Those compositions shown in the foregoing examples were further diluted to $\frac{1}{100}$ with water. Pieces of a knitted fabric made of nylon-6 fibers (product of Toray Co., Ltd. of Japan) were immersed in the solution at the bath ratio of 1:30, at 30° C. for 5 minutes. Then, the pieces of fabric were squeezed to about 50%. After being air-dried at room temperature, they were felt to determine the softness. Thereafter, the treated pieces of fabric were washed with a commercial heavy duty detergent under the washing conditions stated in example. Thereafter, they were soaked for 12 hours in a sufficiently soiled solution prepared by washing soiled underwears with a commercial heavy duty detergent until bubbles ceased to form. After being air-dried at room temperature they were determined of the soil additional density (SAD) ($\log_{10} R_o/R_s$, wherein: R_o represents reflectance before being soiled, and R_s represents reflectance after being soiled). The result is shown in Table 14. From this table, it is known that the compositions of the present invention impart soft feel and antistatic property to laundry.

TABLE 14

	Composition	After treatment		After treatment-washing		SAL ($\times 10^4$)
		Hand feel	Half time of leakage (sec- onds)	Hand feel	Half time of leakage (sec- onds)	
40	(B), Example 1.....	Soft.....	0.1	Soft.....	0.1	43

What is claimed is:

1. A detergent composition, consisting essentially of one of the water-insoluble metal salts of amphoteric surface active agent which are expressed by the general formulas:

1

R represents an alkyl group having 6-30 carbon atoms;
R' represents hydrogen or CH_3 ;
 m represents an integer of 1 to 3.

p represents an integer of 1 to 2;
X represents hydrogen, $(\text{CH}_2)_m\text{COO}$ or
 $(\text{CH}_2)_m\text{COOH}$

M represents an alkaline earth metal;
x, *y* and *z* each represent an integer determined by the
 valency of said metal;
 said water-insoluble metal salt being blended with at least
 one substance expressed by the general formula:

wherein

u, *v* and *w* each represent an integer of 3 to 100;
b represents an integer of 1 to 2;
k represents an integer of 0 to 1;
s represents an integer of 1 to 4;
Me represents an alkali metal or an alkaline earth
 metal;
D represents either $-(\text{CHR}'\text{CHR}'\text{O})_u\text{X}_6$ or
 $\begin{array}{c} \text{R}-\text{CH}-\text{CH}_2 \\ | \\ \text{O}(\text{CHR}'\text{CHR}'\text{O})_u\text{X}_7 \end{array}$
*X*₁ and *X*₂ represent hydrogen, $(\text{CH}_2)_m\text{COO}$ or
 nothing;
*X*₃, *X*₄, *X*₅, *X*₆ and *X*₇ each represent hydrogen or
 $(\text{CH}_2)_m\text{COO}$;
t is 1 when *X*₁ or *X*₂ is hydrogen or $(\text{CH}_2)_m\text{COO}$ and
t is 0 when *X*₁ or *X*₂ is nothing.

2. An aqueous composition consisting essentially of
 the detergent composition of claim 1 being at least partially
 solubilized or dispersed in water.

5 3. A detergent composition according to claim 1, in
 which the said water-insoluble metal salt is one expressed
 by the general Formula III.

4. A detergent composition according to claim 1, in
 which the said water-insoluble metal salt is one expressed
 by the general Formula IV.

10 5. A detergent composition consisting essentially of
 the detergent composition of claim 1 blended with an organic
 sulfate or organic sulfonate detergent.

6. A detergent composition consisting essentially of the
 detergent composition of claim 3 blended with an organic
 sulfate or organic sulfonate detergent.

15 7. A detergent composition consisting essentially of the
 detergent composition of claim 4 blended with an organic
 sulfate or organic sulfonate detergent.
